UNITED STATES PATENT OFFICE.

CARL COERPER, OF COLOGNE, GERMANY.

ARMATURE FOR DYNAMO-ELECTRIC MACHINES.

SPECIFICATION forming part of Letters Patent No. 337,558, dated March 9, 1886.

Application filed June 1, 1885. Serial No. 167,164. (No model.) Patented in France June 10, 1882, No. 166,972; in Luxemburg February 12, 1885, No. 494; in England February 27, 1885, No. 2,671; in Belgium February 28, 1885, No. 67,835; in Italy March 31, 1885, XIX, 17,915, XXXI, 427, and in Spain April 30, 1885, No. 6,920.

To all whom it may concern:

Be it known that I, CARL COERPER, of Cologne, in the Empire of Germany, have invented certain new and useful Improvements 5 in Armatures for Dynamo-Electric Machines, (which have been patented to me in France, No. 166,972, June 10, 1882; Belgium, No. 67,835, February 28, 1885; England, No. 2,671, February 27, 1885; Luxemburg, No. 494, 10 February 12, 1885,) of which the following is a specification.

This invention relates to armatures for dynamo-electric machines; and it consists of a flat-ring armature for dynamo-electric machines, which is made of a closed ring-shaped hollow frame, around which is wound a filling of insulated wire, said frame being tapering at the inner end and inclosed at the three 15 sides by the pole-pieces of the field-magnets. 20 The flat rings are supported on a disk or web of paper attached to the shaft of the armature.

In the accompanying drawings, Figures 1 to 11 are cross-sections of pole-pieces of different shapes, all being designed with a view to inclose the armature at the circumference and sides. Figs. 12 and 13 are vertical transverse sections of my improved armature, shown as arranged with one and two rings; 25 and Fig. 12^a is a cross-section of the hollow frame of the armature-ring.

Similar letters of reference indicate corresponding parts.

a a in the drawings represent the pole-pieces of the field-magnets of a dynamo-electric machine, of which one or more may be arranged, according to the number of flat rings of which the armature is composed. The shape of the pole-pieces *a a* corresponds to 35 the cross-section of the armature-rings, and is so devised that the pole-pieces surround the armature-rings at three sides—namely, at the circumference and the two sides adjoining the same—as shown in Figs. 1 to 11. 40 The construction of the armature is illustrated in Figs. 12 and 13 and 12^a. It consists of a disk or web, *d*, of paper, a hollow closed ring-shaped frame, *b*, and a filling of insulated iron wire, which last two form the induction 45 core or ring of the armature. When the 50

armature-ring is made rectangular at its circumference, as shown in Fig. 12, the pole-pieces have to be made to correspond to the same, as shown in Fig. 4. When they are rounded off, the pole-pieces correspond thereto, as shown in Fig. 1. Several flat rings may be arranged sidewise of each other on the supporting disk or web *d*, in which cases the pole-pieces extend in the spaces between the rings, as shown in Figs. 1, 2, and 3. The wires forming the filling of the hollow frame are made of magnetically or of magnetically and electrically insulated iron wire and then closed at the outer end. The flat-ring armatures are made tapering at their inner circumference, so as to reduce the layers of wire not exposed to the exciting action of the pole-pieces, and are attached to the paper disk or web *d* by means of screws, clamping-rings, angle-pieces, or other suitable devices. (Not shown in the drawings.) The disk or web *d* is keyed to the shaft in any approved manner.

Having thus described my invention, I claim as new and desire to secure by Letters Patent—

1. An induction-ring for armatures of dynamo-electric machines, consisting of a closed ring-shaped hollow frame, and of a filling of insulated iron wire in said frame, substantially as set forth.

2. An induction-ring for armatures of dynamo-electric machines, consisting of a closed ring-shaped hollow frame, tapering at its inner circumference, and a filling of insulated iron wire wound in said frame, substantially as set forth.

3. An armature for dynamo-electric machines, consisting of a supporting web or disk of paper keyed to the center shaft, and one or more flat induction-rings having a tapering inner circumference, said ring or rings being made of a hollow frame and a filling of insulated iron wire, substantially as set forth.

In testimony that I claim the foregoing as my invention I have signed my name in presence of two subscribing witnesses.

CARL COERPER.
